attorney

UNITED STATES PATENT OFFICE.

RICHARD LICHTENBERGER, OF NEVIGES, NEAR VELBERT, GERMANY.

PADLOCK.

Application filed December 22, 1926, Serial No. 156,370, and in Germany July 12, 1926.

The present invention relates to a padlock the case of which has a U-shaped form and which is provided with a straight locking-bolt contained in one arm of the U portion 5 and displaceable transversely therein.

The object of the invention is to provide a pivotally mounted lever, the end of which engages the bolt, retaining the bolt in its withdrawn position, when the padlock is 10 open, by means of a spring and on the bolt being shot home actuating the catch consisting of a hook which holds the bolt in the closed position and can only be released by the key belonging to the padlock. Several 15 embodiments of construction of the padlock of the present invention are shown in the accompanying drawings in which:—

Figure 1 is an elevation of the padlock, provided with a steel protected barrel, with 20 the bolt shot home.

Figure 2 is an elevation of the same padlock with the bolt withdrawn and the staple of a hasp, which is not shown, inserted between the branches of the barrel.

Figure 3 shows one half of the barrel of the padlock with the locking mechanism, the bolt being shot home and secured.

Figure 4 shows the same half of the barrel and locking mechanism when the bolt is 30 withdrawn.

Figure 5 is a modified form of construction and shows one half of the barrel of the padlock when the locking mechanism is of a type which allows a flat key to be inserted at one end. The bolt is in the locked position.

Figure 6 shows the same half of the padlock barrel of Figure 5 with the bolt withdrawn.

Figure 7 shows one half of a padlock barrel provided with a further type of locking mechanism in which the bolt is secured in its two end positions by chubb locking plates, the bolt being shot home.

Figure 8 shows the same padlock when the bolt is unlocked.

The barrel of the padlock is composed of two steel sheets stamped into a U shape and pressed into hollow shells, these being joined together by caps fitting tightly over the two ends of the barrel.

A bolt 3 is movably mounted in an arm or branch 1 of the U-shaped barrel of the

padlock. An opening or slot 5 is provided in the wall 4 of the second branch 2 of the 55 barrel opposite the arm or branch 1, into which the front end 7 of the bolt 3 passes on the bolt being shot home. The space between the two arms or branches 1 and 2 of the barrel is empty when the padlock is 60 open.

In order to secure a hasp, placed over a staple in the usual manner, the padlock with the bolt 3 withdrawn, is pushed over the staple 6 until the latter is situated between 65 the two arms or branches 1 and 2, as shown in Fig. 2, when the bolt 3 is pushed home, passing through the opening of the staple and thus securing the hasp, which is not shown.

A lever 9, pivotally mounted in the barrel of the padlock on a pin 8, the end 10 of which lever engages within a slot provided in the bolt 3, serves to move the bolt 3 backwards and forwards, as shown in Figures 3 75 to 8. A plate 12, the forward end of which is formed as a hook 13, is pivotally mounted on a pin 11 fitted on the lever 9 (Figs. 3 and 4).

A lug 14 is provided on the upper edge 80 of the hook on the plate 12 whilst one end 15 of a leaf spring located on the pin 8 bears against this lug 14, the other end 29 of the spring resting against the rear wall 16 of the barrel of the padlock.

When the bolt 3 is pushed home, the hook 13 on the plate 12 engages the pin 17 secured on the barrel of the padlock and is held in this position by the spring 15, 29. The plate 12 in turn holds the lever 9 together with the locked bolt 3, as shown in 90 Fig. 3.

The padlock is opened by rotating the plate 12 about the pin 11 by means of a key 18 until the hook is raised off the pin 17. 95 In its path of rotation the key strikes the lever 9 which rotates about the pin 8 and on further turning of the key thus moves the plate 12 along with it under increasing tension of the spring 15, 29, the end 10 of the 100 lever 9 thus moving the bolt 3 into the unlocked position as shown in Fig. 4. In this position of the lever 9, the wards of the key rest in a curved depression 19 in the edge of the lever 9 and thus lock the latter. 105 When the key is turned backwards, it

forces the plate 12 to the left, the lever 9 being moved along with it and in turn driving the bolt 3 home. As soon as the end of the hook 13 comes in front of the pin 17 during the movement of the plate 12, the latter engages the pin 17 by means of the hook 13 under the action of the stretched spring 15, 29, whereby the lever 9 and the bolt 3 are secured in the locking position.

In the modification of the padlock shown in Figs. 5 and 6, two transverse walls 20 and 21 are mounted in the barrel and are provided with slots which in combination with a socket element 22 in the end 35 of the barrel, serve to guide a flat key 23. This key has a slotted edge 24 which, on turning the key, slides over a projection 25 on a partition 36 arranged between the partitions 20 and 21. A pin 28 is located on the lever 9, against which the rear half 29 of the leaf spring contacts. A forwardly bent lug 27 is provided on the front edge of the plate 12, the wide part 26 of the key catches under this lug 27 when the key is turned thus lifting the plate 12 forward against the tension of the spring 15-29 so that the hook 13 is lifted off the pin 17. The lever 9 is now turned to the right by the branch 29 of the stretched spring, moving the bolt 3 along with it and thus opening the padlock. The plate 12 is also moved a certain distance. The hook 13 slides with its lower edge on the pin 17, against which it is forced by the spring arm 15 pressing on the lug 14 on the plate 12.

The movement of the lever 9 required to open the padlock is limited by the lug 27 on the plate 12 contacting with the transverse wall 20.

The padlock can be closed without using the key, as it is merely necessary to move the bolt 3 by hand. The lever 9 is moved forward by this action and the plate 12 moves along with it. As soon as the under edge of the hook 13 reaches the pin 17, the plate 12 is rotated downwards by the spring arm 15 so that the hook 13 engages the pin 17 and thus secures the locked position of the bolt 3.

The modified form of the padlock shown in Figs. 7 and 8 can also be locked without a key. The two arms of the spring are replaced in this type by separate springs 15 and 29. The spring 29 actuating the lever 9 is arranged so that it permanently tends to move the lever 9 together with the bolt 3 into the open position. The spring 15 causes the plate 12 to engage the pin 17 and holds it in this position during the locking operation.

The locked position of the bolt 3 is secured also by a number of chubb tumblers 30, in addition to the plate 12, which are pivotally mounted on the pin 17 and are forced by the spring 31, bearing against a

pin 32, against a pin 33, fixed on the lever 9, on which they are guided by means of an angular slot 34. When the bolt 3 is locked, the pin 33 is located in the vertical arm of the angular slot 34. 70

The padlock is opened by a suitable key fitting in the lock which disengages the plate 12 and the tumblers 30 are so positioned that the horizontal portion of the angular slots are covered and the pin 33 comes to rest 75 in the forward end of the horizontal portions of the angular slots covering each other, whereon the lever 9 is immediately rotated backwards by the spring 29. The bolt 3 also partakes of this movement. 80 When the key is removed, the padlock can be locked by simply forcing the bolt 3 home. The locking elements take up the positions shown in Fig. 7, in which they are retained by the pin 33 which again passes into the 85 upper arm of the angular slot 34 and the engaged hook of the plate 12.

The barrel of the padlock is preferably formed, in all the examples of construction shown, of two pieces of plate stamped out 90 in the form of a letter U and pressed into a hollow shell shape, which are connected together by two caps 37 (Figs. 1 and 2) tightly fitted over the two ends of the barrel.

The space left between the two branches 95 of the U is adjusted in each case to the thickness of the staple, so that padlocks of this type can be used for all the metal fittings of a door consisting of hasps which are met with in practice. 100

Claims.

1. In a padlock, in combination, a two-armed lock-case having the inner and outer walls of one of its arms perforated to receive the locking-bolt; a straight locking-bolt adapted to operate through said perforated arm and to enter into an opening in the inner wall of the second arm of the lock-case; a lever pivotally mounted and adapted to move the locking-bolt; a plate pivotally connected with the said lever and having a hook adapted to engage a fixed pin, said plate being arranged to be actuated by a key so as to disengage the hook; and a spring for retaining the hook in the locked 105 position of the bolt. 110

2. In a padlock, in combination, a two-armed lock-case; a straight locking-bolt having a slot to receive the upper end of the lever adapted to move the said bolt; a plate pivotally connected with the said lever and having a hook adapted to engage a pin fixed to the lock-case, said plate being arranged to be actuated by a key so as to disengage the hook; and a spring adapted to move the 115 said lever so as to automatically open the lock. 120

3. In a padlock, in combination, a two-armed lock-case; a straight locking-bolt; a lever adapted to move the said bolt provided 125 130

with a pin arranged to engage the angular slots of tumblers pivotally mounted on a pin fixed to the lock-case, a plate pivotally connected with the said lever and having a hook adapted to engage the said fixed pin; the plate and the tumblers being arranged to be actuated by a key so as to disengage the hook from the fixed pin and the pin engaging the tumblers from the vertical part of the angular slots of the tumblers. In testimony whereof, I have signed my name to this specification at Neviges this 4th day of December 1926.

RICHARD LICHTENBERGER.
